PADDING RACK FOR PAPER STOCK

Kenneth J. Dollahite, Fort Worth, Tex.

Application March 24, 1951, Serial No. 217,375

8 Claims. (Cl. 11—1)

1

This invention relates to the printing and binding arts, and it has particular reference to a padding or tabbing rack for paper stock, and its principal object resides in the provision of a device for supporting stacks of paper stock which has been prepared for binding or gluing into pads of uniform or predetermined thicknesses, as printed forms, bank checks and drafts, memo pads, and the like, and secure the sheets of the stock in proper alignment in the stacks to facilitate the gluing operation.

It is an object of the invention to provide a padding rack of simple and economical design which is capable of accommodating stacks of paper stock cut into uniform sheets of different sizes and provide means for aligning the edges of such sheets to insure precision in their unitary assembly into pads and for the application of a padding compound, or other suitable binding materials, to their edges on one side of the stack.

Another object of the invention is that of providing a rack which is pivotally supported on a movable base so that it is capable of being loaded from one side, which is open, and affording racking or guide doors on the opposite side, against which the stock is arranged and properly aligned, and which can be opened or swung back to expose the secured stocks for gluing.

A still further object of the invention resides in the provision of a padding rack which is capable of being inclined from a vertical position on either side of its pivotal axis, and rearwardly thereof, to more readily retain the stacked paper stock while the same is secured by adjustable clamps for the gluing operation.

While the foregoing objects are paramount, other and lesser objects will become manifest as the description proceeds, taken in connection with the appended drawings wherein:

Figure 1 is a front elevational view of the invention showing the racking case in loading position and illustrating the adjustable stock-retaining clamps slidably secured in the sides of the case.

Figure 2 is a side elevational view of the invention, showing the racking case in its vertical rotative position, and showing the vertical standard and guide frame at the top.

Figure 3 is a plan view of the device illustrating the guide frame and locking device for securing the racking case against rotation.

Figure 4 is a plan view of one of the clamps and a fragmentary lateral cross-sectional view through one side wall of the case illustrating the guide strips for the clamps.

2

Figure 5 is a transverse sectional view of the invention showing the clamps in plan and the positions of the open guide doors.

Figure 6 is another side elevational view of the invention showing the racking case inclined rearwardly from its rotative axis.

Figure 7 is a front view of the invention showing the racking case inclined rearwardly and to one side, and showing a stack of paper stock arranged therein, an opposite inclined position being shown in dotted lines, and

Figure 8 is a plan view of the base, the standard being shown in lateral section, and illustrating an arrangement of embossing defining shallow compartments for accessories and supplies.

In conventional padding operations it is common practice among printers to arrange the prepared paper stock in suitable stacks on tables, using weights, and other devices, for retaining the stacks in proper alignment for the application of the padding compound. Such facilities are impractical and unsatisfactory because it is difficult to maintain the stock in proper alignment and there is the hazard of losing the stack under the crowded conditions of some shops. Moreover, the old method of stacking the stock on bindery tables for tabbing usually consumes valuable space and time.

The present invention is designed to afford a readily movable racking case which is so mounted as to provide a mechanism capable of being operated with great ease and by persons who need not be particularly skilled in the printing art, because the device affords a means for retaining the stock so that it is substantially self-aligning, requiring a minimum of manual effort. It will also become apparent that a plurality of stacks of different size sheets can be processed in the device at one operation.

The invention, therefore, comprises a rectangular frame or case 10 adapted to be positioned and operated in substantially vertical positions. The case 10 has closed sides 11 and 12, and top and bottom members 13 and 14, the operative sides of the case 10 being open except for a pair of guide doors 15 and 16 attached by hinges 17 to the side members 11 and 12 to partially close the padding side of the case, as illustrated in Figures 1 and 7.

The doors 15 and 16 are shown in open position in Figure 5, the hinges 17 being sectional and having double pivots 18 so that the doors 15 and 16 can be swung well back on either side of the case. Tensioned latches 19 secure the doors 15

3

and 16 at the top and bottom of the case 10 while the stock 20 is being placed therein.

The case 10 is pivotally supported by a spindle 21 attached by a flange 22 to the bottom 14 thereof, the lower end 23 of the spindle 21 being rotatably seated in a bearing 24 in a base 25, the latter having a plurality of casters 25' to facilitate moving the assembly. The base 25 has a front portion 26 on which is defined a plurality of shallow compartments 27, 28 and 29, by embossed ribs 30, to accommodate certain accessories, such as glue and water pots, extra clamps, and the like. An open frame portion 31 extends rearwardly from the portion 26 and supports a standard 32 which is secured thereto by bolts 33.

The standard 32, shown more clearly in Figures 1, 2 and 6, comprises a casting formed with angular sides 34 and suitable angular bracing members 35. Foot members 36 provide means for securing the standard 32 to the base 25 by the bolts 33. To the upper end of the standard 32 is secured a guide frame 37 by bolts 38, the frame 37 being shown in detail in Figure 3 and which will be presently described.

Secured to the top 13 of the case 10 is a casting 39 which is formed with a flange 40 for attaching the same by bolts, or other suitable device. Integral with the upper end of the member 39 is an annular flange or ring 41 which provides a pivot for the upper end of the case 10. The guide frame 37, a plan view of which is shown in Figure 3, is formed with a plurality of semi-circular recesses with which the member 41 conforms. When the pivot member 41 is located in the recess 42, forwardly of the frame 37, which is in vertical alignment with the bearing 24 on the base 25, the case 10 can be rotated on its pivots 21 and 41.

Directly behind the recess 42 is another similar conformation 43 which will receive the member 41 to permit the case 10 to be inclined in the manner shown in Figure 6. When the member 41 is placed in either of the recesses 44 and 45 the case 10 can be inclined to either side, as illustrated in solid and dotted lines in Figure 7. The flanged member 41 has a pair of diametrically opposed slots 46 into which is arranged a threaded rod 47, one end of which is connected to a hinge 48 which is pivotally secured between a pair of brackets 49 attached by bolts 50 to the guide frame 37 rearwardly from the recess 42.

The opposite or free end of the rod 47 is arranged, when the case 10 is locked in a vertical position as in Figures 2 and 3, in a notch 51 defined by a pair of integral spaced lugs 52 on the front of the frame 37, the nuts 53 and 54 being adjustable along the rod 47 to properly space the same. Thus, the case 10 is rigidly secured against rotation or against displacement from the recess 42. The case can be locked in rigid position in the same manner when turned 180 degrees, or reversed on its pivots 21 and 41. The rod 47 is also employed to rigidly lock the case 10 in the inclined position shown in Figure 6, or when the member 41 is in the recess 43.

In operation, therefore, the case 10 should be positioned so that the guide doors 15 and 16 are to the rear, as depicted in Figures 1, 2 and 7, which shall be hereinafter referred to as the loading position. In such position the stock 20, which is cut into sheets of uniform size, is stacked and secured by one of a pair of clamps 55 which are slidably attached to the sides 11 and 12 by bolts 56 arranged in the slots 57 defined between steel strips 58 secured to the inner surfaces of the side

4

members 11 and 12, as shown in Figure 4. A groove 59 is provided longitudinally of each of the side members 11 and 12 to accommodate the heads of the bolts 56 and winged nuts 60 are threaded upon the bolts 56 by which the clamps are rigidly secured against the stacked stock 20.

Each of the clamps 55, which are interchangeable, has an auxiliary clamp or plate 61 suspended therebeneath by screws *a*, *b*, *c*, and *d*, and when the clamps are impressed upon the stock 20, the plate members 61 can be manipulated to more securely hold the stock in position by the thumb screws 62. The clamps 55 are shown in Figures 1, 4, 5 and 7, and can be removed from the slots 57 at their lower ends which are spaced above the bottom 14 sufficiently to release the bolts 56.

One of the objects of the invention is that of providing a medium through which the stacked paper stock can be properly aligned and it is often desirable to jog the stock against one of the sides and one of the guide doors. This can be more readily accomplished by tilting the case 10 to either side of its axial pivots, in the manner shown in Figure 7, as previously described. It is apparent that when one stack is secured in the case 10 the latter can be tilted to the opposite side, as illustrated in dotted lines in Figure 7, and another stack installed.

After the stock 20 is properly arranged in the case the upper pivot 41 is returned to the recess 42 and the case 10 rotated 180 degrees to bring the doors 15 and 16 to the front of the structure and the latching rod 47 is placed in operative position to hold the case rigid. The doors 15 and 16 can then be opened and the padding compound applied to the stock 20. In this position the stock is flush with the edges of the side members 11 and 12 and the bottom 14. The stock is divided into units by separating boards 63 which may be employed as backing boards for the pads.

When two stacks of stock of different dimensions are to be processed in the case 10, and one stack is composed of larger sheets than those of the other stack, an auxiliary clamp of lesser dimension may be substituted for one of the clamps 55, the other of which may overlap the smaller sheets while the smaller clamp is used to depress the sheets of lesser dimension in the companion stack. The auxiliary clamp can be deposited in the central compartment 28 on the base 25, the compartments 27 and 29 being provided for the glue and water pots 64 and 65, shown in Figures 6 and 7. The device can be made stationary by locking the casters 25' by any suitable device, such as the members 66.

Obviously, certain modifications in the structure can be resorted to by persons skilled in the art, and certain accessories may be added without departing from the spirit and intent of the invention or the scope of the appended claims.

What is claimed is:

1. In a padding rack for printers and book binders, a stacking case for paper stock, a base having a supporting standard secured thereto and extending vertically from the rear of said base, a guide frame connected to the upper end of said standard and extending forwardly over said base, the said case having a spindle attached to its bottom and supporting said case for rotation above said base, an annular flange member secured to the top of said case providing an upper pivot therefor in said guide frame, con formations in said guide frame adapting said upper pivot to be shifted to different positions there-

in, means for locking said pivot in one of said conformations, and a pair of guide doors hinged to one side of said case.

2. In a rack for padding paper stock, in combination, a case formed with side, top and bottom members and having vertical pivots on said top and bottom, a supporting base for said case having a socket formed therein for the lowermost pivot and a standard extending upwardly from the rear of said base, a guide frame attached to the top of said standard and formed with a plurality of seats for the uppermost of said pivots whereby said case can be inclined toward said standard and to either side of the axis of said pivots, a pair of hinged guide doors on one of the open sides of said case, and adjustable clamps slidably arranged in said case to secure stacks of paper stock in said case for padding.

3. In a padding rack for paper stock, in combination, a case having its front and back open and having pivots on its top and bottom, a base supporting said case for pivotal operation and a standard extending vertically from its rear portion, a guide frame attached to the upper end of said standard and extending horizontally over said case, the said frame being formed with a plurality of seats for the uppermost of said pivots whereby to support the upper end of said case in any of several inclined positions relative to the axis of said pivots, and a pair of guide doors hinged to said case for closing one of said open sides.

4. In a padding rack for paper stock in printing shops, in combination, a stacking case having two open sides and a pair of guide doors hinged on one side to close the same, a base supporting said case having casters thereon, a standard attached to said base and rising vertically from the rear thereof, a guide frame secured to the top of said standard and extending forwardly over said base, a pivot on the top and bottom of said case and means in said base to receive said bottom pivot, the said guide frame having a plurality of seats formed therein for said top pivot whereby to support the upper end of said case in different inclinations from its pivotal plane, and means on said guide frame for locking said case in its pivot against rotation.

5. In a padding device for paper stock, the combination comprising a case defining a rectangular frame having open sides and a pair of hinged guide doors on one of said sides, a movable base for said case, a standard connected to the rear side of said base and extending ver-

tically therefrom, a guide frame attached to the upper end of said standard and extending forwardly over said base, a spindle on the bottom of said case having a bearing on said base and providing for rotation of said case, an annular flanged member on the top of said case providing an upper pivot therefor, means formed in said guide frame for pivotally retaining said flanged member, conformations in said guide frame adapting said case to inclinations rearwardly and to either side of the vertical axis of said case, and means on said guide frame for locking said case against rotation.

6. In a rack for padding paper stock, a stacking case having upper and lower pivots adapting the same for rotation on a vertical axis, a movable base for said case having a vertical standard thereon, a guide frame attached to the top of said standard providing a bearing for said upper pivot on said frame, a plurality of horizontal recessions formed in said guide frame for receiving said upper pivot whereby to provide for the inclination of said case rearwardly from and to either side of the vertical rotative axis of said case, a pair of guide doors hinged to one side of said case providing a backing for said paper stock therein, a pair of adjustable clamps in said case for retaining said paper stock therein, and means attached to said guide frame for locking said upper pivot against rotation.

7. In a padding rack for paper stock, in combination, a stacking case comprising a rectangular frame having open sides and a pivot member on its upper and lower ends, a movable base for said case providing a bearing for said lower pivot and a standard secured to said base and rising vertically therefrom, a guide frame attached to the upper end of said standard providing a bearing for said upper pivot, the said guide frame having a plurality of conformations defining seats for said upper pivot to support said case in different inclinations from a vertical pivotal axis, means on said guide frame for locking said case in vertical position and against rotation, and a pair of guide doors hinged to one of the open sides of said case.

8. In a padding rack, as described in claim 7, having a pair of adjustable clamps in said case whereby to retain stacks of paper stocks therein for padding.
